UNITED STATES PATENT OFFICE.

FRANK W. TERPENING, OF ST. LOUIS, MISSOURI.

ROOFING OR SIDING.

SPECIFICATION forming part of Letters Patent No. 767,723, dated August 16, 1904.

Application filed January 29, 1904. Serial No. 191,234. (No model.)

To all whom it may concern:

Be it known that I, FRANK W. TERPENING, a citizen of the United States, residing in the city of St. Louis, in the State of Missouri, have invented certain new and useful Improvements in Roofing or Siding, of which the following is a full, clear, and exact description, reference being had to the accompanying drawings, forming part of this specification.

10 My invention relates to that class of ready-made roofing or siding which is composed of a series of layers of impervious material rendered waterproof by the application of cement thereto, the present invention having reference to roofing or siding sheets of this character in which is incorporated a layer of wire fabric to add strength and resistance to wear incident to the handling and service of the roofing or siding.

15 The invention consists in features of novelty hereinafter fully described and pointed out in the claim.

Figure I is a perspective view of a section of my improved roofing or siding. Fig. II is a fragmentary view of one of the roofing or siding sheets, partly broken out to illustrate the various layers of material incorporated therein. Fig. III is an enlarged section of one of the roofing or siding sheets.

20 A designates sheets of my improved roofing or siding, each of which is provided at one end with a lap surface B. The roofing or siding sheets are each composed of a bottom layer 1 of fibrous wool-felt, onto which is laid a layer or coating 2 of cement, such as asphalt. Above the layer 2 of asphalt is a layer or sheet 3 of wire fabric, which is surmounted by a layer or coating 4 of cement, such as asphalt. The layers of cement 2 and 4 permeate into the 25 mesh of the wire-fabric sheet 3 and furnish adhesion between said wire fabric and the bottom layer of wool-felt, thereby rendering the sheet of roofing or siding intact throughout. Onto the topmost layer 4 of cement I apply a 30 layer 5 of crushed granite, gravel, or other suitable granular material, which by embed-

ding into the topmost layer of cement becomes an integral part of the roofing or siding sheets. At one end of each roofing or siding sheet I omit the topmost layers of cement and granular material for the purpose of furnishing the lap surface B, thereby exposing the adjacent portion of the wire fabric 3, so that the next adjoining roofing or siding sheet may be positioned over said lap surface, as illustrated 35 in Fig. I, the lap surface being designed to receive a coating of cement just previous to the assemblage of the roofing or siding sheets in the process of applying them upon a roof or the side of a building, as will be readily understood. It will be seen that by continuing the wire fabric to the lap surface of each sheet of roofing or siding the strength afforded thereby is included at the lap surface of each sheet and that, moreover, the cement freshly 40 applied to the wire fabric in the process of laying the roof or siding will enter into the mesh thereof, providing for additional degree of adhesion due to the greater quantity of cement that it is possible to apply over the 45 wire-fabric surface.

It will be seen that the cement upon the upper face of the layer 1 of felt is exposed at the lap B through the sheet of wire fabric 3, and therefore when an additional coating of 45 cement is applied to the lap it will cause the cement previously on the lap to become heated, whereby the old and fresh layers of cement combine to afford greater tenacity of adhesion between the lap 1 of the roofing or siding sheet and the adjoining surmounting roofing or siding sheet positioned over said lap. By continuing the wire fabric to form the lap portion of the sheet I obtain greater strength at said lap than is possible where the lap portion is provided, due to the discontinuance of the top layer of the sheet only to expose a lower layer of fabric or paper, as has been heretofore proposed, this being an important feature, inasmuch as the lap portion is necessarily weakened by discontinuing the portion of the sheet thereat, and it is highly impor-

tant that the strength at the lap portion, which is the weakest part of the sheet, be reinforced to the utmost possible degree.

I claim as my invention—

- 5 A roofing or siding sheet composed of wool-felt, cement, wire fabric, cement and granular material, arranged in layers from bottom to top in the order named, and having a lap

portion composed of wool-felt, cement and wire fabric arranged in layers from bottom to top in the order named.

FRANK W. TERPENING.

In presence of—

E. S. KNIGHT,
BLANCHE HOGAN.
